AUTOMOBILE ORNAMENT

Eric P. Ramstrum, Grosse Pointe Farms, Mich.,
assignor to Detro Products, Inc., Grosse Pointe
Farms, Mich., a corporation of Michigan

Application March 29, 1949, Serial No. 1,689

Term of patent 3½ years

(Cl. D14—18)

To all whom it may concern:

Be it known that I, Eric P. Ramstrum, a citizen of the United States, residing at Grosse Pointe Farms, Wayne County, Michigan, have invented a new, original, and ornamental Design for an Automobile Ornament, of which the following is a specification, reference being had to the accompanying drawings, forming a part thereof, wherein:

Fig. 1 is a perspective view taken from the rear and one side and showing my design for an automobile ornament;

Figs. 2 and 3 are rear and side elevations, respectively, thereof; and

Fig. 4 is a top view thereof.

I claim:

The ornamental design for an automobile ornament, as shown.

ERIC P. RAMSTRUM.
